UNITED STATES PATENT OFFICE.

ORLANDO HOPKINS NASON, OF MARTHA FURNACE, PENNSYLVANIA.

NECK-YOKE.

No. 902,160.

Specification of Letters Patent.

Patented Oct. 27, 1908.

Application filed June 16, 1908. Serial No. 438,845.

To all whom it may concern:

Be it known that I, ORLANDO H. NASON, a citizen of the United States, residing at Martha Furnace, in the county of Center and State of Pennsylvania, have invented certain new and useful Improvements in Neck-Yokes, of which the following is a specification, reference being had to the accompanying drawings.

19 My invention relates to improvements in harness and more particularly to neck yokes.

The object of the invention is to provide an improved neck yoke device for a double harness which will take the strain caused by holding back and backing from the animals' necks and place it upon the breeching.

With the above and other objects in view, the invention consists of the novel features of construction and the combination and arrangement of parts hereinafter fully described and claimed, and illustrated in the accompanying drawings, in which

Figure 1 is a perspective view illustrating the use of my improved neck yoke device in connection with a double harness; and Fig. 2 is a detail view of one of the roller carrying rings or clips upon the ends of the auxiliary neck yoke.

In the drawings 1 denotes a portion of a draft pole on which is mounted in the usual manner a main neck yoke 2 which carries two auxiliary neck yokes 3.

4 denotes the breeching of a double harness and 5 denotes the hames. The latter are connected to the ends of the main neck yoke 2 by straps 6 and rings or clips 8 and the breeching 4 has forwardly extending straps 7 connected to the auxiliary neck yokes 3. Each of the rings or clips 8 is preferably constructed of a metal rod bent into U-shape to receive one end of the main neck yoke and having the ends of its parallel arms 9 bent to form eyes 10. The latter receive a transverse rivet, bolt or the like 11 which forms the journal of a roller 12. This roller is of cylindrical form and corresponds

in length to the space between the arms 9. The clip or loop 8 is retained upon one end of the main neck yoke by a staple or the like 13 and the roller 12 is engaged by one of the hame straps 6. The breeching straps 7 have snap hooks at their forward ends connected to rings 14 on the auxiliary neck yokes. The latter are connected at their centers by clips 16 to kinks or loops 15 formed in one of the arms 9 of each of the clips 8. These kinks or loops are formed by bending the arm 9 at a point about midway its length, as more clearly shown in Fig. 2.

From the foregoing it will be seen that when my improved neck yoke device is used upon a double harness, as shown in Fig. 1, the strain caused by holding back and backing is taken almost entirely from the hames and placed upon the breeching and that by providing the clips 8 with the rollers 12 and the loops or kinks 15 there will be little or no wear upon the hame straps and both the latter and the breeching straps will be held in their proper positions.

Having thus described my invention what I claim is:

The combination with the hames and the breeching of a double harness, of a main neck yoke, auxiliary neck yokes carried thereby, clips at the ends of said main neck yoke, each of said clips being of U-form and having a roller journaled between its arms and one arm formed with a loop, breast straps extending from the hames and passed around said rollers, clips engaged with the loops of said clips and connected to the auxiliary neck yokes and breeching straps leading from the breeching and engaged with the ends of the auxiliary neck yokes.

In testimony whereof I hereinunto affix my signature in the presence of two witnesses.

ORLANDO HOPKINS NASON.
